US00D864969S

(12) **United States Design Patent** (10) **Patent No.:** **US D864,969 S**
(45) **Date of Patent:** **** Oct. 29, 2019**

(54) **CARD PC**

(71) Applicant: **Intel Corporation**, Santa Clara, CA
(US)

(72) Inventors: **Aleksander Magi**, Aloha, OR (US);
David M. Collins, Portland, OR (US)

(73) Assignee: **Intel Corporation**, Santa Clara, CA
(US)

(**) Term: **15 Years**

(21) Appl. No.: **29/639,752**

(22) Filed: **Mar. 8, 2018**

Related U.S. Application Data

(62) Division of application No. 29/569,414, filed on Jun. 27, 2016, now Pat. No. Des. 815,099.

CLAIM

The ornamental design for a card PC, as shown and described.

DESCRIPTION

FIG. 1 is an environmental view of the device with a docketing station, the docking station not being a part of the claim;

FIG. 2 is a top perspective view of the device in FIG. 1; FIG. 3 is a bottom perspective view of the device in FIG. 1;

FIG. 4 is a top planar view of the device in FIG. 1;

FIG. 5 is a bottom planar view of the device in FIG. 1;

FIG. 6 is a right side planar view of the device in FIG. 1;

FIG. 7 is a left side planar view of the device in FIG. 1, and opposite of FIG. 6;

FIG. 8 is a front planar view of the device in FIG. 1; and, FIG. 9 is a back planar view of the device in FIG. 1.

Broken lines in the drawings are included for the purpose of illustrating environmental structure only and form no part of the claimed design.

1 Claim, 7 Drawing Sheets
